PORTABLE COMBINATION BEER COOLER
AND DISPENSERGeorge E. Miles, Cincinnati, and Edward C. Miles,
North College Hill, Ohio, and Albert E. Bathi-
any, Jr., Newport, Ky.

Application May 26, 1934, Serial No. 727,742

13 Claims. (Cl. 225—18)

The object of our invention is to provide a simple, compact, efficient, convenient and economical single unit for cooling, treating and dispensing beer for home use.

5 Our invention consists in providing a temperature-insulated container having a beer coil mounted therein with cooling means therefor, a receptacle mounted in said container and adapted to receive a carbonic acid gas pressure flask 10 together with means for discharging said carbonic acid gas into a barrel of beer whereby the beer is charged and forced out through said coil for use. Our invention also consists in the construction, combination, location and arrangement of parts 15 as herein set forth and claimed.

In the drawing:

Fig. 1 is a side elevation partly broken away and partly in section to show the interior construction of the apparatus;

20 Fig. 2 is a front elevation with part of the barrel broken away; and

Fig. 3 is a section on the line 3—3 of Fig. 1.

In the embodiment of our invention as illustrated and which shows a preferred construction, 25 we provide a container 1 having double walls 2 and 3 containing mineral wool 4 or other suitable insulating material for the purpose of retaining cold and excluding heat, said container having a lid 5 also provided with double walls 2' and 3' 30 containing mineral wool 4' or other suitable insulating material. The lid is preferably provided with a knob 6 as a convenient handle for placing and removing said lid and also to present an attractive appearance.

35 A coil tube 7 is vertically mounted within the container 1 adjacent the inner wall 3 and extends from the inner end of the outlet or discharge faucet 8 near the top and is connected near the bottom of the container to tap rod or tube 9 40 which extends downwardly into barrel 10 through reinforcing and container-supporting tube 11. Said tap rod extends downwardly to the bottom of the barrel and is provided with the usual perforations 12 near its lower end through which 45 the beer is discharged from the barrel through said tap rod or tube.

50 Receptacle 13 is mounted centrally within container 1 and preferably extends down some distance below the bottom thereof. Said receptacle is provided with a removable cap 14. A space 15 is formed between coil 7 and receptacle 13 wherein cracked ice 16 is packed for the purpose of cooling the beer as it is drawn upwardly within container 1 through coil 7 and tap rod 9. Recep- 55 tacle 13 is provided for the purpose of receiving

carbonic acid gas pressure flask 17 having a discharge outlet 18 below its valve 19 at the top and detachably connected with tube 20 extending downwardly through the bottom of said receptacle 13 into control valve 21 having gauge 22 5 thereon and thence into hose or flexible tube 23 which is suitably connected to the usual or standard beer tap 24 mounted in the head 10' of barrel 10.

The carbonic acid pressure gas enters the tap 10 at 25 and passes downwardly therethrough around the tap tube 9 upon the top of the beer 26 through space 25' between the tap and tap rod. Emergency valve 27 is mounted at the inlet of hose or flexible tube 23. A removable drip cup 15 28 is mounted in socket 29 upon tube 11 to receive any drippings from discharge faucet 8. Container 1 is supported by reinforcing and supporting tube 11 and by two adjustable legs 30 and 31. A plug 32 is mounted on the inner end of the faucet to which coil 7 is connected for the purpose of access to the interior of the coil for cleaning and sterilizing.

When it is desired to draw beer from the barrel 10 having this apparatus mounted thereon, 25 open the main or top valve 19 of the carbonic acid gas pressure flask 17 and regulate the pressure desired on top of the beer by means of control valve 21, the desired pressure being indicated by gauge 22. The carbonic acid pressure gas within 30 flask 17 is discharged downwardly through tube 20 and control valve 21 into flexible tube 23 and thence through tap 24 upon top of the beer 26 in barrel 10, the beer being forced out from the bottom portion of the barrel through tap rod 9 35 into cooling coil 7 and out through dispensing faucet 8. The forcing of the carbonic acid gas downwardly upon and through the beer serves the purpose of giving life to the beer and preventing it from becoming flat. Its pressure also forces the beer out of the barrel, tap tube, coil and discharge faucet. The coil packed with ice in the space between container 1 and receptacle 13 insures the serving of the beer in delightfully cool and refreshing drafts. This apparatus is a 40 simple, convenient and desirable means of dispensing and cooling beer in the home as it enables the user to mount it upon the keg or barrel of beer and to serve the beer in a cool, delectable and refreshing manner with the proper smack.

Thus it will be seen that by the use of our invention any unskilled person can mount the apparatus upon a beer barrel and operate it with ease and facility.

As is well known, the pleasant taste and life of 55

beer depends upon the carbonic acid gas it contains when supplied in barrels and it will retain all of its original gas besides absorbing an additional amount by the carbonic acid pressure gas which we use to force the beer out of the barrel which will improve its quality.

An important advantage of our invention consists in constructing and combining the several parts comprising our portable combination beer cooler into a single compact unit which is adapted to be easily and conveniently applied to a barrel or keg of beer and operated with facility by any person without the requirement of special skill or instructions.

15 Our invention is capable of some modification without material departure from its scope or spirit as defined in the claims.

What we claim as new and desire to secure by Letters Patent is:

20 1. In a portable combination single unit beer cooler and dispenser, an insulated container having cooling means therein, a receptacle in said container, a carbonic acid gas flask enclosed within said receptacle, a carbonic acid gas discharge tube connected to said flask, a control valve and gauge to which said tube is connected, a coil tube within said container, a discharge faucet connected at one end to said coil, a tap rod connected to the other end of said coil and extending into a barrel of beer, a tube leading from said control valve into said barrel of beer whereby carbonic acid pressure gas is discharged therein to charge said beer and force it through said tap rod, coil and discharge faucet for use.

25 35 2. In a portable combination single unit beer cooler and dispenser, an insulated container, a receptacle in said container, a carbonic acid gas flask mounted within said container, a carbonic acid gas discharge tube connected to said flask, a control valve to which said tube is connected, a coil tube within said container, a discharge faucet connected to said coil, a tap rod connected to said coil and extending into a barrel of beer, a tube leading from said control valve into said barrel 40 of beer whereby carbonic acid pressure gas is discharged therein to charge said beer and force it out through said faucet for use.

45 3. In a portable combination single unit beer cooler and dispenser, a container, a receptacle in said container, a carbonic acid gas flask in said receptacle, a carbonic acid gas pressure discharge tube connected to said flask, a control valve to which said tube is connected, a barrel, a tube leading from said control valve into said barrel of beer, a coil tube mounted between said container and receptacle with a space therein for receiving a cooling agent, a tap rod connected to said coil and extending into said barrel of beer and a discharge faucet connected to said coil.

50 60 4. A portable combination single unit beer cooler and dispenser comprising a container having a beer coil therein and having means for cooling beer as it passes through said coil, a barrel, discharge means connected to said coil and means 65 for receiving beer therethrough from the barrel, in combination with a receptacle in said container having means for receiving carbonic acid pressure gas and means for discharging said pressure gas into a barrel of beer to charge the beer and 70 force it out through said coil.

55 75 5. In a portable combination single unit beer cooler and dispenser, a container having a receptacle mounted therein, a carbonic acid gas pressure flask mounted in said receptacle, a coil tube mounted within said container and having suit-

able discharge means, a tap rod extending into a barrel of beer and connected to said coil, a tube leading from said flask into said barrel of beer, and means for controlling the flow and pressure of said carbonic acid gas to charge said beer and force it out through said tap rod, coil and discharge means.

6. In a portable combination single unit beer cooler and dispenser, an insulated container having an insulated removable lid therefor, a receptacle mounted in said container, a carbonic acid gas pressure flask therein, a valve-controlled tube leading from said gas flask into a barrel of beer, a coil tube mounted within said container in spaced-apart relation from said receptacle whereby a space is formed for receiving ice therein, a discharge faucet connected to said coil, a tap rod or tube connected to said coil and extending into a barrel of beer whereby the beer is adapted to be charged by carbonic acid pressure gas and forced outwardly through said coil and cooled as it passes therethrough.

7. In a portable combination single unit beer cooler and dispenser, a container adapted to have cooling means therein, a coil mounted in said container and having suitable discharge means and means for receiving beer therein from a barrel, a receptacle in said container, a carbonic acid gas flask in said receptacle and means for discharging carbonic acid gas therefrom into said barrel of beer whereby the beer is charged and forced outwardly and cooled through said coil.

8. In a portable combination single unit beer cooler and dispenser, a container adapted to receive and cool beer as it passes therethrough, a tap rod mounted in a barrel of beer through which the beer passes into said container, adjustable legs on which said container is mounted and supported along with said tap rod, and means for discharging carbonic acid gas into the barrel of beer and charging and forcing said beer outwardly to be dispensed.

9. In a portable combination single unit beer cooler and dispenser, an insulated container having an insulated removable lid, a carbonic acid gas pressure flask, a receptacle in said container having a removable cover to receive said flask, a coil tube mounted within said container in spaced-apart relation from said receptacle, and adapted to have ice mounted in said space, a discharge faucet connected to said coil, a tap tube connected to said coil and extending into a barrel of beer whereby said container is partly supported, adjustable legs adapted to complete the support of said container upon said barrel of beer, a tube leading from said gas pressure flask into said barrel, and means for controlling and indicating the flow of gas therethrough.

10. In a portable combination single unit beer cooler and dispenser, a container having insulated walls, a coil tube mounted vertically in said container adjacent the inner wall thereof, a discharge faucet connected to the upper end of the coil tube, a tap rod or tube connected to the lower end of said coil tube and adapted to extend into a beer barrel, a receptacle mounted in the central portion of said container and adapted to have ice packed between said receptacle and said coils, a lid for said receptacle, a carbonic acid gas pressure flask mounted in said receptacle, a valve in its top, a tube extending from said flask downwardly and outwardly through said receptacle, a control valve connected to said tube, a gauge connected to said control valve, a tap mounted in the head of a beer barrel and a tube connecting said

tap to said control valve, whereby carbonic acid gas under pressure is forced downwardly upon and through the beer whereby it is revivified and reinvigorated and forced through the tap tube, 5 coil and discharge faucet.

11. In a combination cooler and dispenser, a container provided with a vertically disposed coil mounted adjacent its interior wall and having a central vertical space therein, a tap rod connected 10 to the lower end of said coil and extending into a beer barrel and a discharge faucet connected to its upper end, a receptacle mounted in said container in spaced-apart relation from said coil, a carbonic acid gas pressure flask detachably 15 mounted within said receptacle and having connection with the interior of a beer barrel whereby carbonic acid gas may be discharged

downwardly from said flask into the barrel to charge the beer and force it outwardly through said tap rod, coil and discharge faucet, substantially as and for the purposes specified.

12. In an apparatus as specified in claim 11, a tube surrounding said tap rod and attached adjacent the lower end of said container and to said tap, and adjustable legs cooperating with said tube to support said apparatus in proper position upon a barrel head. 10

13. In an apparatus as specified in claim 11, a removable drip cup mounted below the discharge faucet and adapted to catch any drippings from the faucet. 15
